PERRY WEARNE, OF RIXHEIM, GERMANY.

DESIGN FOR WALL-PAPER.

SPECIFICATION forming part of Design No. 35,402, dated December 3, 1901.

Application filed November 5, 1901. Serial No. 81,262. Term of patent 7 years.

To all whom it may concern:

Be it known that I, PERRY WEARNE, a subject of the King of Great Britain, residing at Rixheim, Alsace, Germany, have invented and produced a new and original Design for Wall-Paper, of which the following is a specification, reference being had to the accompanying drawing, forming a part thereof, in which is represented a section of wall-paper showing my design.

The design in its entirety consists of elongated panels A and smaller panels B, surrounded by a border C, appearing with scroll-work, the large panels A being ornamented with a garland of flowers D, and each small panel B being ornamented by flowers E of the forget-me-not type.

The leading feature of the design consists of the garland of flowers in a panel surrounded by a border appearing with scroll-work. 20

Having described my invention, I claim as new and desire to secure by Letters Patent—

The design for wall-paper herein shown and described.

In testimony whereof I have signed my 25 name to this specification in the presence of two subscribing witnesses.
